UNITED STATES PATENT OFFICE.

MARTIN L. KORS, OF CHICAGO, ILLINOIS.

AEROPLANE.

1,098,735.

Specification of Letters Patent.

Patented June 2, 1914.

Application filed August 22, 1913. Serial No. 736,052

To all whom it may concern:

Be it known that I, MARTIN L. KORS, a citizen of the United States, residing at Chicago, in the county of Cook and State of Illinois, have invented new and useful Improvements in Aeroplanes, of which the following is a specification.

This invention relates to improvements in aeroplanes.

10 More especially it relates to improvements in devices for stabilizing and in other respects controlling aeroplanes while in flight.

In aeroplanes as now customarily built the machine is kept upright in flight by warping the ends of the planes, or by otherwise bending or turning the main or auxiliary planes about an axis transverse to the line of flight. By thus increasing the angle of incidence of the plane upon the air an increased lifting component is obtained and also an increased resistance to forward motion which tends to turn the machine about on its vertical axis, which if not properly met, will not only progressively change the direction of flight but may ultimately result in causing the machine to fall. Hence a counter-correction is applied by operating the rudder of the machine. The degree of lateral diversion varies, depending upon many factors so that there is no precise relation between the degree of warping applied to correct stability and the degree of rudder turning or counter-correction that must be applied simultaneously, and the proper adjustment varies also as a tipped machine regains equilibrium, so that the incessant attention of the aviator is required, and sometimes also a high degree of skill, with an ever present danger that the operator may

40 become confused or may err in judgment as to whether manipulation of the correction or of the counter-correction is needed, or as to the relative degree in which these two elements should be moved.

45 It is one object of this invention to simplify these problems by eliminating the necessity for a coöperating movement of the laterally-acting rudder. Both the warping and the rudder action impose a wasteful drag upon the machine, consuming a certain amount of power, delaying progress and putting heavier stresses upon the structure. As the departures from equilibrium are incessant this extra stress of recovery is incessant, and subject to sudden changes, being greatest whenever the danger of tipping too

far is greatest. As there are natural limitations upon the weight and strength of parts, this extra stress diminishes, to an appreciable, although perhaps indeterminate, percentage the factor of safety in an aeroplane. It also increases the power required, above that which might otherwise be necessary, reduces the carrying capacity, and tends to the more rapid exhaustion of the 65 aviator's physical and mental powers of control of the machine.

It is another object of the present invention to eliminate these objections to aviation, as now practised, by providing a stabilizing device which eliminates the drag occasioned by the warping, and the augmentation of stress in time of danger from tipping.

It is also the object to diminish the extra 75 demand upon the power plant for regaining stability, resulting in increase of speed or carrying capacity with a given power, to diminish the strength of parts needed, and to reduce the degree of skill requisite of the 80 aviator for maintaining stability, and to produce a style of control of the apparatus which will lend itself more readily to automatic governing.

It is a further object of the invention to 85 attain the other advantages that characterize structures embodying the invention, among which may be mentioned the ability to effect an ascent or descent of the machine independently of the rudder heretofore always provided for that purpose; and the provision for manipulation with certainty and positiveness upon the exercise of force by the aviator vastly less than that hitherto required.

95 The objects of the invention are accomplished by providing devices in the nature of valves to relieve the supporting air pressure under that side of the aeroplane which is too high, thus utilizing the force of gravity instead of operating against it; by arranging these valves, in the form of one or more units, as shutters pivoted on axes parallel to the direction of flight and by nearly balancing them individually on their pivots; 100 by providing so that these valves form a part of the effective lifting plane when closed, and may be opened to varying degrees as desired, in either main plane to control lateral stability, or in both main planes 105 to control the longitudinal stability; by providing so that these valves are automatically

opened by the main air pressure when permitted by the operator, voluntarily or involuntarily, and yet, being nearly balanced, can be closed by him by an exertion of 5 strength corresponding to only a fraction of their lifting power; by providing vanes for steadyng the valves when opened; and by other features that will appear from the construction disclosed herein.

10 In the accompanying drawings which represent an embodiment of the invention somewhat diagrammatically: Figure 1 is a plan of a monoplane; Fig. 2 is a perspective view, showing a fragment of the plane, with 15 the valves open, on a larger scale; and Fig. 3 is an elevation showing a detail in section on the line 3—3 of Fig. 1, enlarged.

Referring to the drawings, which represent the application of the invention to a 20 monoplane of well known type, the planes on opposite sides of the machine are marked 10 and 10' respectively, and are joined to the frame 11 which carries a seat 12 for the aviator, an engine 13, a propeller 14 25 and any other ordinary or suitable appliances, such as rudders (not shown) for directing the course of the machine in the horizontal plane and in the vertical plane. Toward the lateral extremity of each of the 30 main planes 10, 10', are arranged the valves, in two units 15, 15, on one side of the machine and in two correspondingly placed units 15', 15', on the other side of the machine. These valves are so arranged as to 35 form part of the main planes when closed, and, being set in the midst of their respective planes, contribute to the support of the machine in the air in proportion to their respective areas. They are pivoted, as represented at 16, on axes running fore and aft of the machine near the middle of each valve so that they are capable of opening 40 as illustrated in Fig. 2. They may, obviously, be designed so that either the inboard or the outboard edge opens upward; and so that they are balanced upon their respective pivots to any desired degree of perfection, and so that the unbalanced edge is that which opens upward or that which opens 45 downward. In the construction illustrated the upward pressure of air under the main planes 10, 10', tends to open the inboard edges of the valves upward, the area of each valve lying inboard from its pivots being 50 slightly larger than that lying outboard. The force with which the air tends thus to open them is dependent upon the degree to which the area on one side of the valve pivot exceeds the area on the 55 other side and is therefore only a small fraction of the total lifting force of the air under the valve. The cord 17, by which the valves 15 may be drawn to and held in their closed positions is connected with any 60 suitable device arranged in a convenient po-

sition for control by the aviator. The particular device illustrated is a pedal 18 placed on the opposite side of the plane, laterally, from the valves 15, the corresponding cord 17, leading from the valves 15 and crossing 70 to the side of the plane remote laterally from them, is also seen, its pedal being marked 18'. If the valves be considered as being a foot wide, the drawing represents five inches of that width as being on the 75 outboard side of the pivot and seven inches on the inboard side of the pivot; and of the latter, five inches balance the five inches first mentioned and two inches are unbalanced. This unbalanced area is extended by auxiliary vanes 19, preferably arranged in sections, which may be of aluminum or other suitable material, attached to the top of the valve and projecting still farther inboard. When the valve is closed these vanes shut 80 down close upon the top of the plane, as seen clearly in Fig. 3. They are then ineffective, for the valve itself is then seated against surfaces 20 prepared for it on the cross ribs of the main plane and no air from 85 below has access to them. But when the valve is open, as illustrated in Fig. 2, so that air is rushing up through the opening and against the under sides of the vanes 19, these auxiliary vanes furnish an additional area 90 against which the rush of air presses upward, thus fortifying the unbalanced two inches in tending to keep the valve pressed steadily open, so far as the cord 17 will 95 allow.

It will be understood that as the drawings are merely explanatory the proportions of parts are distorted in some respects in order to represent the parts on as large a scale as possible, leaving it for the constructor of an aeroplane embodying the invention to design the actual dimensions of his parts according to his particular needs; but it may be mentioned here that it is believed that in good practice the space between a pair of valves 15, 15, will be generally designed wider than that represented. The general idea to be held in mind in designing this part of an aeroplane is that a wide opening of the valves 15, 15, is equivalent to cutting 105 off a certain length of the outboard ends of the planes, viz., the part occupied by the valves and including in the portion cut off the space 24 between the valves. This will be true whenever that space 24 is narrow 110 enough for the air pressure under it to be relieved by the proximity of the open valve. The degree of proximity illustrated will accomplish that, and it is believed that experiment will show that a space 24 which is 115 nearly twice as wide as the adjacent valves will thus be relieved of its lifting power. The mounting of the valves consists of ferrules surrounding the front and rear edge bars of the main plane, carrying the studs 120 130

16 which constitute the pivots of the valves. The bearings of the valves on these pivots may be strengthened by supplementary outriggered bearings 22, but it will be obvious 5 that any other suitable form of mounting might be adopted.

In operation the aviator normally holds the pedals 18, 18', depressed, thus drawing all of the valves to their closed positions. 10 When the machine is in flight there is air pressure upward against the under surfaces of the planes 10, 10'. To correct a tipping of the machine toward either side the aviator releases somewhat his pressure on the 15 pedal 18, or 18', whichever is on the lower side, whereupon the air pressure acting upward on the unbalanced parts of valves on the higher side of the machine immediately opens those valves to whatever extent 20 the release of the pedal permits. The air support on that side of the plane is immediately reduced owing to the escape of air through the openings thus made, while the support of the plane on the other side of 25 the machine remains unchanged. When the support of the upper side of the apparatus has been sufficiently reduced that part of the apparatus will begin to sink downward because the force of gravity has become 30 slightly superior to the uplifting force. The rate of sinking is not that of a fall under the influence of the full force of gravity, but is gentle, depending on what may be called the "net" force of gravity, 35 which may be controlled and varied by opening the valves on the high side to a greater extent to increase it; or by closing them to decrease it; and it is obvious that a machine can be made with planes and 40 valves of suitable proportions to accomplish this to any degree or refinement of accuracy that may be desired. The motion by which the aviator accomplishes this is naturally executed correctly by him because it 45 is instinctive to incline his body toward the side which is higher, thus withdrawing his foot pressure from the side which is lower. The tipping of the plane therefore gives him automatic indication as to which 50 valves ought to be opened. It is to be noted that the restoration of equilibrium is thus accomplished without warping or otherwise changing either plane so as to change its angle of incidence to the air in forward 55 flight. Hence there is no deflection of the apparatus from its true course of flight and no tendency to turn about a vertical axis; and no counter-correction is necessary of 60 the sort provided in other apparatus by resort to the rudder. Consequently the speed of the forward flight is not materially affected by the stabilizing operation, because no drag is imposed either by the valves 15 nor by a counter-correcting rudder. In 65 fact the correction consists merely in re-

lieving the excess pressure on the high side, which is a process of reducing stresses, in contradistinction to the remedy applied in aeroplanes of the now prevalent type, by warping the planes, which is in effect 70 an increasing of tension on one side of the apparatus to balance and exceed an already excessive pressure on the other side. The elimination of the rudder manipulation necessary in a plane controlled by warping or 75 the like makes an important simplification in the degree of skill required of the aviator, for heretofore the lateral equilibrium has been dependent upon the inter-relation of three independent and constantly changing forces, two of which, the warping and the rudder, have to be combined by the aviator into a resultant that will neutralize or correct the third, which is the wind, and 80 numerous other causes that tend to disturb 85 equilibrium. With the apparatus of the invention there is only a single variable, the valves, which the aviator need change in order to combat the other variable, the tendency of equilibrium to be disturbed, which 90 is a much simpler proposition than is the combining of two variables to that end. It is a further advantage of the invention that the apparatus operates with great ease and certainty; and to this end those features 95 by which the valves are opened by the air pressure, the operator, however, having to restrain only a fraction of the entire lifting force of the valves, and are strictly controllable as to degree opening and are 100 practically free from friction in operation, are important. The general effect of opening the valves is the same as eliminating a proportional amount of the area of the aero-plane. For example, when both valves 15 105 are wide open the area of the plane between them and to the left of them in Fig. 1 will afford little or no support to the apparatus, because the air impinging thereon flows out instantly through the valve openings. Hence the area of the plane from the nearest valve 15 to the center should be 110 designed to afford whatever support is considered a necessary minimum, the remainder of the plane being capable of adding 115 any desired increment of supplementary support, up to the full area with the valves closed. Obviously the valves may be made in units of any desired size and gradation as may be deemed expedient.

While the operation described has been one of stabilizing, laterally, and upon the assumption that their valves would normally be closed, except when that on the high side is opened, the apparatus might be 125 operated by maintaining both somewhat open normally, and then opening the high valves and closing the low valve for restoration of stability, thus getting quicker results. Rapidity of results can also be en- 130

- hanced by simultaneously moving the elevating rudder. This rudder will not of itself affect the lateral equilibrium, but by tipping both planes upward it changes their angles of incidence equally and so increases the preponderance of lifting effect of that one of them whose valves are closed. And while the valves are provided primarily for preserving or recovering lateral balance it is possible to use them as a substitute for manipulation of the elevating rudder, to control longitudinal balance. For that purpose the valves on both sides are to be opened or closed together and equally. The head of the machine will then sink or rise with respect to the rear float or rudder. This is a safeguard to which resort can be had in case the control cords of that rudder become jammed.
- 20 While the invention has been illustrated as it may be applied to a monoplane operated by motor, it is obvious that it is not limited to that type of plane, nor to motor driven apparatus, and it will be understood

that many variations may be made from 25 the specific embodiment of the invention here disclosed without departing from the scope of the invention or of the appended claim, the purpose of which is to cover whatever of patentable novelty exists in the invention disclosed.

I claim as my invention:—

In a flying machine the combination of supporting surfaces with valves adapted to release a portion of the air supporting 35 them; said valves being individually nearly balanced with respect to the effect of said supporting air when seated; and vanes on the valves extending beyond their seats on that side of the supporting surfaces from 40 which they open, thereby steadyng the valves when open.

Signed by me at Boston, Mass., this fifteenth day of August, 1913.

MARTIN L. KORS.
